CLAIM

The ornamental design for a pet toy, as shown and described.

DESCRIPTION

FIG. 1 is a front perspective view of a pet toy in accordance with my new design;

FIG. 2 is a bottom perspective view thereof;

FIG. 3 is a top perspective view thereof;

FIG. 4 is a top view thereof;

FIG. 5 is a bottom view thereof;

FIG. 6 is a right side view thereof; and,

FIG. 7 is a left side view thereof.

The broken lines depict portions of the pet toy which form no part of the claimed design.
